US00D529903S

(12) **United States Design Patent** (10) **Patent No.:** **US D529,903 S**
(45) **Date of Patent:** **** Oct. 10, 2006**

(54) **GATEWAY HOUSING**

(75) Inventors: **Matthew B. McRae**, Laguna Beach, CA (US); **Calvin Y. Liu**, Irvine, CA (US); **Donald T. Mah**, Trabuco Canyon, CA (US)

(73) Assignee: **Cisco Technology, Inc.**, San Jose, CA (US)

(**) Term: **14 Years**

(21) Appl. No.: **29/224,587**

(22) Filed: **Mar. 3, 2005**

(51) **LOC (8) Cl. 14-03**

(52) **U.S. Cl. D14/240**

(58) **Field of Classification Search** 379/387.01, 379/399.01, 413.02, 413.04, 430, 431, 433.01, 379/420.03, 957, 52, 106.1, 333-337; D14/240, D14/242, 246, 192, 223, 140.1, 140.4; D13/184; 181/129-130; 455/569.1, 510, 524; 439/717

See application file for complete search history.

(57) **CLAIM**

The ornamental design for a gateway housing, as shown and described.

DESCRIPTION

FIG. 1 is a top and front perspective view of a gateway housing showing our new design;

FIG. 2 is a top and rear perspective view thereof;

FIG. 3 is a top plan view thereof;

FIG. 4 is a bottom plan view thereof;

FIG. 5 is a front elevation thereof;

FIG. 6 is a rear elevation thereof;

FIG. 7 is a side elevation thereof; and,

FIG. 8 is a side elevation of the side opposite that shown in FIG. 7.

The broken lines in the figure drawings are for illustrative purposes only and form no part of the claimed design.

1 Claim, 3 Drawing Sheets
